(57) **CLAIM**

The ornamental design for a lamp shade, as shown and described.

DESCRIPTION

FIG. 1 is a top, front and right side perspective view of a lamp shade showing my new design;

FIG. 2 is a bottom, rear and left side perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is an enlarged view of the portion labeled "9" in FIG. 2.

The dot dash dot broken lines shown in the drawings illustrate boundaries of the enlarged view and form no part of the claimed design. The evenly spaced broken lines depict portions of the lamp shade that form no part of the claimed design.
